UNITED STATES PATENT OFFICE.

BENJAMIN L. GARY, OF MADISON, NEW JERSEY.

NUT-LOCK.

1,122,901.

Specification of Letters Patent. Patented Dec. 29, 1914.

Application filed February 18, 1914. Serial No. 819,507.

To all whom it may concern:

Be it known that I, BENJAMIN L. GARY, a citizen of the United States, residing at Madison, in the county of Morris and State 5 of New Jersey, have invented certain new and useful Improvements in Nut-Locks; and I do hereby declare the following to be a full, clear, and exact description of the invention, such as will enable others skilled in 10 the art to which it appertains to make and use the same.

My invention relates to new and useful improvements in nut locks and consists of simple and inexpensive nut locking means 15 which positively prevents rotation of the nut and which may be locked in a most reliable and expeditious manner.

My invention aims to improve nut locks of the character described so as to render 20 them more simple as to construction, reliable and efficient in operation, cheap to manufacture and commercially desirable.

The above and additional objects are accomplished by such means as are illustrated 25 in the accompanying drawings, described in the following specification and then more particularly pointed out in the claims which are appended hereto and form a part of this application.

With reference to the drawings, wherein 30 I have illustrated the preferred embodiment of my invention as it is reduced to practice, and throughout the several views of which similar reference numerals designate corre- 35 sponding parts: Figure 1 is a side view of my improved nut lock showing it in assembled position, Fig. 2 is a side view showing my nut lock in assembled position and at right angles to Fig. 1, Fig. 3 is an end view 40 of the device showing the locking plate removed, Fig. 4 is a view similar to Fig. 3 with the locking plate in assembled position, Fig. 5 is a detail perspective view of the locking plate, and Fig. 6 is a detail perspective view of the locking member that is arranged to coöperate with the locking plate 45 illustrated in Fig. 5.

Referring to the drawings the numeral 1 50 designates a bolt having a head 2, screw threaded terminal 3 and being flattened upon opposed sides as at 4 at its screw threaded terminal 3, for a purpose which will be later more fully described. A nut 5 is turned upon the screw threaded terminal 55 3 of the bolt 1. The nut 5 is provided upon one face with a plurality of radial grooves

6 extending from the edge of the bolt receiving aperture in the nut to the outer edge thereof.

A locking member designated 7 as an entirety is adapted to be mounted upon the bolt 1 and arranged to hold the nut 5 in locked position. This member 7 consists of a single piece of preferably resilient wire that is bent intermediate its ends to form 60 segmental base portions 8 and 9 arranged in spaced opposed relation to each other and formed integral with a curved bolt engaging loop 10 that is disposed between the portions 8 and 9, is approximately U-shaped 65 and designed to engage and partly encircle the bolt 1.

The members 8, 9, and 10 are all arranged in the same plane. The free ends of the member 7 are bent at right angles to the 70 portions 8 and 9 and provide spaced parallel arms 11 and 12.

A locking plate 13 having an approximately rectangular central opening 14 is adapted to be mounted upon the bolt 1 and 75 engage the outer grooved face of the nut 5. This plate 13 is preferably elongated and provided with L-shaped slits 15 upon opposed sides of the opening 14 which enable the provision of downwardly struck locking 80 tongues 16. The locking tongues 16 are arranged to fit within certain of the grooves 6 in the outer face of the nut 5. The longitudinal edges of the opening 14 are provided centrally of their ends with recesses 85 17 of sufficient size to accommodate the arms 11 and 12 formed on the member 7.

In assembling the nut lock, the member 7 is positioned so that its portions 8 and 9 engage the structure to which the bolt and nut 90 is applied and the U-shaped portion 10 partly encircles the bolt 1. The arms of the U-shaped portions 10 are adapted to engage the flat faces 4 of the screw threaded portion 3 of the bolt 1, while the arms 11 and 12 100 are adapted to lie parallel to and in engagement with the flat faces 4. In this connection it will be noted that the arms 11 and 12 are flattened so as not to interfere with the proper operation of the nut 5. After the 105 member 7 is positioned as described upon the bolt 1, the nut 5 is turned upon the bolt until it is adjusted to the desired position. When the nut is in such position the locking plate 13 is fitted upon the extended portion 110 of the bolt 1 and arranged so that the locking tongues 16 fit within certain of the

grooves 6 in the nut 5. The nut 5 being previously arranged so that the grooved face is outermost. When the plate 13 is positioned upon the bolt 1 and arranged to engage the outer face of the nut 5 the arms 11 and 12 are positioned within the recesses 17. These arms 11 and 12 are of sufficient length to extend considerable distance beyond the outer face of the plate 13 and are bent as at 18 to lie upon the outer face of the plate 13 as clearly shown in Fig. 4. The bending over of the ends of the arms 11 and 12 provide for the secure locking of the nut against rotation. The base portions 8 and 9 of the member 7 are as before stated interposed between the inner face of the nut and the structure to which the bolt and nut is applied.

It will be readily seen with reference to the foregoing description and accompanying drawings, that my improved nut lock may be readily arranged in locking position and moved out of locking position when it is desired to remove the nut and that the nut is positively held against rotation.

The member 7 is held against rotation by the engagement of the U-shaped portion 10 with the bolt 1 after the manner described. The approximately rectangular opening 14 provided in the locking plate 13 prevents rotation of the plate upon the bolt as the bolt at the screw threaded portion 3 is formed approximately rectangular by forming the flat faces 4, described.

It will be readily seen by the locking arrangement described that the nut is positively held against rotation and permitted ready removal from the bolt when desired.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

What is claimed:—

1. A nut lock comprising a bolt, a nut turned upon said bolt and having one face formed with a plurality of radial grooves, a locking member arranged between the inner face of the nut and structure to which said bolt is applied and having arms extending

parallel with and engaging opposite sides of said bolt and terminating beyond the outer face of said nut, a washer plate mounted upon said bolt and engaging the outer face of said nut, locking tongues formed on said washer plate and engaging certain of the grooves in said nut, said arms being bent over and engaging the outer face of said locking plate, said locking member being held against rotation relative to the bolt.

2. A nut lock comprising a bolt, having its shank adjacent to one end formed with opposed flat faces, a nut having one face provided with a plurality of grooves turned on said bolt, a locking member mounted upon said bolt in advance of said nut and comprising segmental base portions arranged to engage the inner face of said nut and a U-shaped bolt engaging portion and a pair of spaced arms arranged to engage and extend longitudinally of the flat faces of said bolt through and beyond the outer face of said nut, a centrally apertured locking plate mounted upon said bolt and engaging the outer face of said nut, locking tongues formed on said locking plate and engaging certain of the grooves in said nut, said arms being bent over and engaging the outer face of said locking plate.

3. In a nut lock the combination with a bolt having opposed flat faces formed adjacent one end and a nut having grooves in one face and mounted upon said bolt of a locking member formed of a single piece of wire and being bent intermediate its ends to provide segmental base portions arranged to engage the inner face of said nut, a U-shaped bolt engaging portion formed integral with the base portions and having spaced arms formed integral with the base portions and being flattened and engaging the flat faces of said bolt, said arms extending through and beyond said nut, a centrally apertured locking plate mounted upon said bolt, and tongues formed on said locking plate adapted to engage certain of the grooves in said nut, said locking plate having opposed recesses opening into the central aperture thereof and receiving said arms, said arms being bent to lie upon the outer face of said locking plate.

In testimony whereof I affix my signature in presence of two witnesses.

BENJAMIN L. GARY.
